UNITED STATES PATENT OFFICE.

CLIFFORD EARL ABERNETHY, OF HICKORY, NORTH CAROLINA.

ELECTRIC TRAIN BULLETIN-BOARD.

1,171,915.

Specification of Letters Patent.

Patented Feb. 15, 1916.

Application filed December 4, 1914. Serial No. 875,518.

To all whom it may concern:

Be it known that I, CLIFFORD EARL ABERNETHY, a citizen of the United States, residing at Hickory, in the county of Catawba and State of North Carolina, have invented a new and useful Electric Train Bulletin-Board, of which the following is a specification.

The present invention relates to improvements in electric train bulletin boards, one object of the invention, being the provision of an apparatus of this character, which is controlled by a manually operated master clock so that one or more bulletin clocks may be operated, there being provided one bulletin clock for each train to designate the original arriving or leaving time thereof, the latter being operably connected through electrical means through the master clock, whereby the minutes "late" that train happens upon arrival or departure may be automatically transmitted to the bulletin clock, which as before stated, may be a single clock or a plurality of clocks, there being further provided automatic means set in operation by a manual means at the master clock for resetting such bulletin clock.

A further object of the present invention, is the provision of an electrical connection whereby a single circuit connection is employed for actuating the step-by-step operating magnet of the bulletin clock and for releasing the pawls thereof to permit of the automatic returning of the bulletin clock to its normal position, the electromagnet for actuating the bulletin clock being of lesser strength than the one for releasing the pawls.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a diagrammatic view showing a master clock with one bulletin clock with the various electrical connections. Fig. 2 is a view in elevation of the master clock. Fig. 3 is a side elevation thereof. Fig. 4 is an enlarged detail sectional view showing the connection for man-

ually operating the minute arbor. Fig. 5 is a front elevation showing a plurality of bulletin clocks. Fig. 6 is a side elevation of the frame and skeleton of one of the bulletin clocks. Fig. 7 is a rear elevation of the mechanism for operating the minute arbor thereof and for releasing the pawls to permit the minute hand to return to normal position. Fig. 8 is a sectional view through the spring casing and the minute arbor of the bulletin clock, taken on the line 8—8 of Fig. 6.

Referring to the drawings, the numeral 1 designates the casing of the master clock, which is a manually actuated clock being provided with a shaft 2 controlled by the crank 3, which in turn has a gear 4 for operating the gear 5 connected to and carried by the minute hand arbor 6, said minute hand 7 controlling through the gears 8, 75 the hour hand 9. Thus the manual manipulation of the shaft 2 will move the respective hands 7 and 9 relative to the dial of the master clock. Carried by the minute hand 7 is a resilient contact 10, disposed in the path to engage the respective contact pins 11, which are insulated from the dial of the clock and disposed at the various minute periods of the dial, so that at each movement of the hand 7 to designate a 85 minute, one contact 11 will be engaged, said contact 11 as illustrated in Fig. 1, being connected upon the inner face of the dial by an electric conducting means 12. It will thus be seen that as the minute hand 7 is 90 rotated clockwise or anti-clockwise that the spring contact 10 will wipe the stationary contacts 11 in succession, the purpose of which will presently appear.

The bulletin or controlled clocks 13 are 95 each constructed similarly, and as before stated, any number of these may be operated separately from the master clock or any number of them may be operated in serial order to designate the arrival and leaving 100 time of a certain train, the diagram as shown in Fig. 1, however, showing only one bulletin clock connected for operation from the master clock 1.

Each bulletin clock consists of the base 105 member 14 which supports the cradle 15 which in turn carries the casing 16 in which is mounted the spiral spring 17, one terminal of the spring 17 being connected to the casing 16, while the other terminal is connect- 110

ed to the minute hand arbor 18. The minute hand arbor 18, as in the usual form of clocks, carries the minute hand 19, and through the train of gears 20 operates the hour hand 21. In order that the arbor 18 may be manually operated, the finger receiving member 18' is connected upon the rear extension thereof as illustrated in Fig. 6. Fixed to the minute hand arbor 18 at the rear of the frame 16 is a ratchet wheel 22, which is provided with sixty teeth thus making it possible to hold the same in step with the sixty contact pins 11 of the master clock 1. A lug 23 is formed upon the base 14 and has pivoted therein, by means of the pin 24, the rocking frame or plate 25, which is provided with the limiting projection or lug 26 disposed for movement between the adjusting screws 27 and 28, as clearly illustrated in Fig. 7. Thus the oscillation of the plate or lever 25 is controlled by the adjusting screws 27 and 28. Pivoted at 31 and 32 to be carried by the oscillatory frame or plate 25 are the pawls 33 and 34, the pawls 33 constituting the operating pawl for the ratchet wheel 22 and consequently for operating the minute hand arbor 18 in opposition to the spring 17, while the pawl 34 constitutes the retrograde movement preventing pawl so that the ratchet wheel 22 is locked against a retrograde movement after the same has been moved clockwise due to the oscillation of the frame 25 when attracted through the armature 29 and the electromagnet 30. It will thus be seen that when the electromagnet 30 is energized, that the armature 29 will be drawn thereto and consequently move the frame 25 to the left as viewed in Fig. 7, causing the pawl 33 to rotate the ratchet wheel 22 one tooth, while the terminal of the pawl 34 being nearer the pivotal point 24 will practically remain in a stationary position so that as the tooth of the ratchet wheel 22 passes therebeneath, the succeeding tooth will be engaged thereby and thus the ratchet wheel 22 will be locked against a retrograde movement after the release of the electromagnet 30 and the consequent return of the plate 25 to the position as shown in Fig. 7. Where found necessary a spring may be connected to the plate 25 for holding it in the return position, as shown in Fig. 7.

In order that the respective pawls 33 and 34 may be properly held in contact with the periphery of the ratchet wheel 22, the springs 35 and 36 are provided, while carried upon the inner ends of the ratchets or pawls 33 and 34, are the armatures 37 and 38, which are disposed in attractive relation with the poles of the respective electromagnets 39 and 39' which constitute the pawl releasing electromagnets, both being connected in series so as to be energized simultaneously for releasing both the op-

erating pawl 33 and the retrograde movement preventing pawl 34 from the ratchet 22 so that the spring 17 will return the minute hand arbor 18 and consequently both the minute and hour hands thereof to its 70 normal or adjusted position.

In order that the respective bulletin clocks 13 may be adjusted to change the time of arrival or departure, an adjustable device A is connected so as to limit the movement of 75 the minute hand and thus when the pawls are released will prevent the same from passing therebeyond, so that the bulletin clocks will under normal conditions always remain at the set time of the arrival or 80 departure of the train to which it appertains.

In setting forth the operation of the present system attention is invited to the electrical diagram as illustrated in Fig. 1 85 and in order to describe its operation, the actuating electromagnet 30 will be set forth first. The circuit for controlling the electromagnet 30, includes the ground 40, the conductors 41 and 41', the battery 42, which 90 is of lesser strength than the battery 51, the conductor 43, the minute hand 7, the resilient contact 10 carried thereby, one of the stationary contacts 11, the connecting conductor 12 thereof, the conductor 44, the 95 stationary metallic bar 45 of the actuating selective switch 46, which is attached to and carried by the casing of the master clock 1, the selective switch 47, which is slidably mounted upon the bar 45, the contact 48, 100 which designates which bulletin clock is to be controlled thereby, the conductor 49, the electromagnet 30, the conductor 50 and the ground 40'. Thus when the train bulletin operator moves the switch 47 to engage the 105 contact 48, the minute hand 7 which is manually operated by the operator will when the contact 10 thereof engages the contacts 11 cause the energization of the electromagnet 30, and the consequent oscillation of the 110 plate or frame 25, so that the ratchet wheel 22 will be moved one tooth and consequently cause the minute hand arbor 18 to move the minute hand one space, to indicate that the departure of the train or the arrival 115 thereof was one minute late. It will thus be seen that any number of clocks 13 may be connected in series with the conductors 49 and 50 and that therefore only one is shown as controlled by the switch 47 and 120 the selective contact 48 that any number may be operated at various parts of the railway station as may be deemed advisable.

As soon as the train designated by the 125 bulletin clock 13 has departed or arrived, it is merely necessary for the operator to place the switch member 47 at a space between the contacts 48 of the switch 46 and to then operate the sliding member 54 of the re- 130

lease switch 53, controlling the following circuit: The ground 40, the conductor 41, the battery 51, the conductor 51', the stationary bar 52 of the releasing switch 53, the selective switch member 54 thereof, one contact 55 thereof, the conductors 56 and 49, the electromagnets 39 and 39', the conductors 60 and 50 and the ground 40'. Thus the two electromagnets 39 and 39', which are not sensitive to the lighter current of the electromagnet 30 are energized simultaneously, both the operating pawl 33 and the retrograde movement preventing pawl 34 are moved inwardly so as to release the ratchet 22 to the action of the spring 17 so that the minute hand arbor 18 of the bulletin clock 13 will be operated counter clockwise to return the hand 7 to the normal position.

20 It is the intention of the present invention that a clock be provided for each arrival or departure of the various trains throughout the day and thus place before the passengers or general public a fixed time table 25 and one which will indicate at a glance as controlled from the master clock 1, the minutes late at which the respective trains are expected to arrive or depart, such bulletin clocks being under the direct control 30 of a single master clock at a distant point, thus rendering it unnecessary for the indicating or bulletin clock to be manually controlled as is the present practice.

Although the present device has been described as intended for use only with train bulletins, it is apparent that the same may be connected for operating at any point where it is desired to indicate the normal time of starting and stopping, and means 40 whereby such normal time clocks may be released and returned to its normal position.

What is claimed is:

1. A system of the character described, 45 embodying a master clock having a switch member and an annular series of contacts for the engagement therewith of said switch member, a plurality of displaying clocks each having a spring returned hand, electro-magnetically-operated means for advancing the hand of each displaying clock, means for preventing the return movement of the hand of each displaying clock, electro-magnetically-operated means controlling 50 each second mentioned means, means for electrically connecting the switch member and contacts of the master clock to the first mentioned electro-magnetically-operated means of the displaying clocks, means for 55 energizing the second mentioned electro-magnetically-operated means of the displaying clocks, the fourth and fifth mentioned means including selective switches whereby the displaying clocks may be controlled individually by the master clock.

2. A system of the character described, embodying a master clock having a switch member and an annular series of contacts for the engagement therewith of said switch member, a displaying clock having a spring 70 returned hand, electro-magnetically-operated means for advancing the hand of the displaying clock, means for preventing the return movement of the hand of the displaying clock, electro-magnetically-operated 75 means controlling the second mentioned means, a source of electrical energy and a selective switch connected in series with the switch member and contacts of the master clock and with the first mentioned electro-magnetically-operated means, and a source of electrical energy and a selective switch connected in series with the second mentioned electro-magnetically-operated means.

3. A system of the character described, 80 embodying a master clock having a switch member and an annular series of contacts for the engagement therewith of said switch member, a displaying clock having a spring returned hand, electro-magnetically-operated 85 means for advancing the hand of the displaying clock, means for preventing the return movement of the hand of the displaying clock, electro-magnetically-operated means controlling the second mentioned 90 means, the two electro-magnetically-operated means being connected in parallel, a relatively weak source of electrical energy connected in series with the master clock and electro-magnetically-operated means, and a relatively strong source of electrical energy 95 and a switch connected in series with said electro-magnetically-operated means, the first mentioned electro-magnetically-operated means being operated by the relatively 100 weak source of electrical energy while the second mentioned electro-magnetically-operated means is only operated by the relatively 105 strong source of electrical energy.

4. A system of the character described, 110 embodying a master clock having a switch member and an annular series of contacts for the engagement therewith of said switch member, a displaying clock having a spring returned hand, electro-magnetically-operated 115 means for advancing the hand of the displaying clock, means for preventing the return movement of the hand of the displaying clock, electro-magnetically-operated means controlling the second mentioned 120 means, the two electro-magnetically-operated means being connected in parallel, a relatively weak source of electrical energy and a selective switch connected in series with the master clock and electro-magnetically-operated 125 means, and a relatively strong source of electrical energy and a selective switch connected in series with said electro-magnetically-operated means, the first mentioned electro-magnetically-operated means 130

being operated by the relatively weak source of electrical energy and the second mentioned electro-magnetically-operated means being operated only by the relatively strong 5 source of electrical energy.

5. A displaying clock embodying a spring returned minute hand arbor having a minute hand, a ratchet wheel secured to said arbor, an oscillating lever, electro-magnetic means 10 for oscillating said lever, a pawl carried by said lever and coöperating with the ratchet wheel for advancing the same, and electro-magnetic means carried by said lever for releasing said pawl from the ratchet wheel.

15. 6. A displaying clock embodying a spring returned minute hand arbor having a minute hand, a ratchet wheel secured to said arbor, an oscillating lever, a pawl pivoted to the lever adjacent the free end thereof, and co-operating with the ratchet wheel, a second pawl pivoted to the lever adjacent the pivot thereof and coöperating with the ratchet wheel to prevent the retrograde movement thereof, electro-magnetic means for oscillating said lever, and electro-magnetic means 25

carried by the lever for releasing said pawls from the ratchet wheel.

7. A displaying clock embodying a spring returned minute hand arbor having a minute hand, a ratchet wheel secured to said arbor, 30 an oscillatory lever having an armature, electro-magnetic means for attracting said armature to oscillate said lever, a pawl pivoted to the lever adjacent the free end thereof and coöperating with the ratchet wheel, 35 a second pawl pivoted to the lever adjacent the pivot thereof and coöperating with the ratchet wheel to prevent the retrograde movement thereof, electro-magnets carried by the lever between the pawls, and armatures attached to the pawls and coöperating with said electro-magnets for releasing the pawls.

In testimony that I claim the foregoing as my own, I have hereto affixed my signature 45 in the presence of two witnesses.

CLIFFORD EARL ABERNETHY.
